Primary Examiner — Kathleen L Jones*Assistant Examiner* — Grace Doyle(74) *Attorney, Agent, or Firm* — Daniel M. Cohn;
Howard M. Cohn(57) **CLAIM**

The ornamental design for a plant-growing container, as shown and described.

DESCRIPTION

FIG. 1 is a perspective view of a plant-growing container showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof; and,

FIG. 9 is an enlarged view of FIG. 1.

The dashed broken line showing of portions of the plant-growing container forms no part of the claimed design. The dot-dash broken line indicates a detail view and does not form part of the claimed design.
